US00D511981S

(12) **United States Design Patent** (10) Patent No.: **US D511,981 S**
Miller et al. (45) Date of Patent: **** Nov. 29, 2005**

(54) **SEMICONDUCTOR INTEGRATED CIRCUIT TEST HEAD**

D369,983 S * 5/1996 Fisher et al. D10/80
6,642,729 B2 * 11/2003 Kang et al. 324/754

(75) Inventors: **Wayne H. Miller**, Los Altos, CA (US);
Ichiang Sun, Portland, OR (US)

* cited by examiner

(73) Assignee: **Credence Systems Corporation**,
Milpitas, CA (US)

Primary Examiner—Antoine D. Davis

(**) Term: **14 Years**

(74) Attorney, Agent, or Firm—John Smith-Hill; Smith-Hill
and Bedell

(21) Appl. No.: **29/201,978**

CLAIM

(22) Filed: **Mar. 23, 2004**

The ornamental design for a semiconductor integrated circuit test head, as shown and described.

(51) LOC (8) Cl. **10-04**
(52) U.S. Cl. **D10/80**
(58) Field of Search D10/75, 78, 80,
D10/102; 324/158.1, 756, 761–762; 439/68,
70, 912

DESCRIPTION

(56) **References Cited**

FIG. 1 is a perspective view of a semiconductor integrated circuit test head showing my new design,

U.S. PATENT DOCUMENTS

FIG. 2 is an end elevation thereof, the opposite end elevation
being of corresponding appearance,

D345,705 S * 4/1994 Nesbitt et al. D10/80

FIG. 3 is a side elevation thereof; and,
FIG. 4 is a top plan view thereof.
